(57) **CLAIM**

The ornamental design for a set of mosaic tiles, as shown and described.

DESCRIPTION

FIG. 1 is a front view of a set of mosaic tiles showing my new design according to a first embodiment.

FIG. 2 is right-side view of my new design shown in FIG. 1.

FIG. 3 is left-side view of my new design shown in FIG. 1.

FIG. 4 is top view of my new design shown in FIG. 1.

FIG. 5 is a bottom view of my new design shown in FIG. 1.

FIG. 6 is a front view of a set of mosaic tiles showing my new design according to a second embodiment.

FIG. 7 is right-side view of my new design shown in FIG. 6.

FIG. 8 is left-side view of my new design shown in FIG. 6.

FIG. 9 is top view of my new design shown in FIG. 6; and, FIG. 10 is a bottom view of my new design shown in FIG. 6.

The broken lines depicting diagonal webbing connecting the individual tiles and the non-front surfaces of the tiles represent portions of the set of mosaic tiles that form no part of the claimed design.

1 Claim, 6 Drawing Sheets
